UNITED STATES PATENT OFFICE.

EDGAR W. BREISCH, OF EDGEWOOD PARK, PENNSYLVANIA, ASSIGNOR TO WESTINGHOUSE ELECTRIC & MANUFACTURING COMPANY, A CORPORATION OF PENNSYLVANIA.

RELAY.

Application filed July 9, 1921. Serial No. 483,475.

To all whom it may concern:

Be it known that I, EDGAR W. BREISCH, a citizen of the United States, and a resident of Edgewood Park, in the county of Allegheny and State of Pennsylvania, have invented a new and useful Improvement in Relays, of which the following is a specification.

My invention relates to electrical controlling devices and particularly to electrical relays.

One object of my invention is to provide a relay that shall be actuated to one position when it is first energized and that shall be actuated to another position when it is de-energized and then immediately re-energized.

Another object of my invention is to provide a relay wherein the increase in the resistance of a winding, by reason of the heat caused by current traversing the same, is employed to produce an unbalance between that winding and another winding, that shall serve to actuate the relay to another position when the former winding is de-energized and both windings are then immediately re-energized.

Another object of my invention is to provide a relay, of the above-indicated character, that may be remotely controlled through a single conductor and a single controlling switch to control two separate circuits.

A further object of my invention is to provide a system including the above-mentioned relay whereby two groups of street lamps may be remotely controlled from a control station through a single circuit by means of a single control switch.

In practicing my invention, I provide a relay of the balanced type comprising two windings, two stationary contact members and a movable member that normally engages both stationary contact members, but that is actuated upon the energization of either coil to disengage one of the contact members and to maintain engagement with the other contact member.

By so constructing one of the windings that it shall have less resistance than the other, the relay may be caused normally

to be actuated to the position that is controlled by the winding having the lesser resistance. That winding, however, when energized, becomes so heated that the resistance thereof increases to a value exceeding the resistance of the other winding which is disconnected from the circuit and is, therefore, de-energized.

If the circuit is opened to permit the relay to return to its initial balanced position and is immediately reclosed, the relay will thereupon be actuated to the position controlled by the second winding, since that winding has a lesser value of resistance than the heated former winding and may, accordingly, be energized to a greater degree.

By means of such relay, two circuits may be controlled from a distance through a single circuit and by means of a single control switch.

Similarly, the relay may be adapted to control two circuits that normally include different values of resistance. The windings may be so designed that the electromagnetic force, or the ampere-turns, produced by one winding shall slightly exceed the electromagnetic force produced by the other winding when the windings are respectively traversed by currents of values corresponding to the resistance values of the devices in circuit therewith. Thus, the relay will be actuated to the position controlled by the winding producing the greater force, and the other winding and its circuit will be disconnected from the energizing source.

After the former winding and its circuit are traversed by current and heated thereby, the resistance thereof will increase and correspondingly decrease the current traversing the same. The electromagnetic force of the first winding will thereupon be decreased to a value less than that normally produced by the other winding which is de-energized. If, therefore, the first winding is de-energized to permit the relay to return to its initial position of balance, and both windings are then immediately re-energized, the relay will be actuated to the position controlled by the second winding, that previously has been de-energized.

Figure 1 is a diagrammatic view of an electrical circuit including the relay embodying my invention.

Fig. 2 is a diagrammatic view of an electrical circuit embodying a modified form 5 of the relay shown in Fig. 1, and

Fig. 3 is a diagrammatic view of a modified circuit including the relay embodying my invention.

10 In Fig. 1 are illustrated a group of lamps 6 that normally are lighted during the evening until midnight, and a group of lamps 7 that are lighted after midnight when the lamps of the group 6 are disconnected from 15 the circuit. Energy for the lamps in both groups is provided by a generator 8, and the circuits including the two groups are controlled by means of a relay 9 and a switch 10. The switch 10 is illustrated as 20 a manually-operated switch but it may be of the time-controlled type in order to render the operation of the system automatic.

The relay 9 comprises two actuating 25 windings 11 and 12, two relatively stationary contact members 13 and 14 and a movable member 15 which is controlled by the windings 11 and 12 to effect the engagement between the contact members 13 and 30 14 and corresponding contact members 16 and 17, respectively.

Normally, the contact members 13 and 16 are in engagement and the contact members 35 14 and 17 likewise. Upon the actuation of the movable member 15 by one of the windings, as, for example, the winding 11, positive engagement is effected between the contact members 13 and 16, while the contact members 14 and 17 are disengaged.

40 The windings 11 and 12 are so designed with regard to the resistances of the circuits including the respective groups 6 and 7, that the electromagnetic force produced by the winding 11 will slightly exceed the electromagnetic force produced by the winding 12 when both circuits are simultaneously energized. Upon the closure of the switch 10, therefore, the relay 9 will effect the disengagement of the contact members 14 and 50 17 but will maintain the contact members 13 and 16 in engagement.

The generator 8 and the control switch 10 are located in a control station and are 55 remotely disposed with respect to the relay 9 and the lamps in groups 6 and 7. When the switch 10 is first closed and the lamps in group 6 energized, the resistance of the circuit, including the winding 11 and the lamps in the group 6, is increased by reason of the heating developed therein by the current. The current traversing that circuit is, therefore, decreased and the electromagnetic force produced by the winding 11 is correspondingly decreased to a value that 60 65 is less than the normal value of the electro-

magnetic force produced by the winding 12.

If the switch 10, therefore, is opened and immediately reclosed, the relay 9 will return to its initial position of balance and will be immediately actuated to the other position that is controlled by the winding 12, by reason of the greater electromagnetic force produced by that winding.

By means of the relay described above, the two groups of lamps may be remotely 75 controlled through a single circuit by means of the single switch 10.

In Fig. 2 of the accompanying drawings is illustrated a similar circuit that contains a modified form of the relay that is illustrated in Fig. 1. In this figure, the relay 19 comprises, in addition to the actuating windings 11 and 12 and the stationary contact members 13 and 14, a flexible conducting member 20 that normally engages both 80 contact members 13 and 14 but is controlled by means of the pivoted member 21 upon which it is mounted to engage only the contact member 13, when the winding 12 is energized, and only the contact member 14, 85 when the winding 11 is energized. Otherwise, the operation of this relay and the circuit illustrated is similar to the operation described in connection with the circuit that is illustrated in Fig. 1.

90 In Fig. 3 of the accompanying drawings is illustrated a circuit including the relay shown in Fig. 2, but differently connected, whereby the operation of two separate circuits may be controlled from a distance in 100 a manner similar to that already described. The winding 11^a of the relay 19 is so constructed of conducting material having a relatively large temperature coefficient that 95 normally its resistance is less than the resistance of the winding 12^a.

105 When the switch 10 is closed, the relay 19 will be actuated to effect engagement of the contact members 14 and 20. After the winding 11^a is heated and its resistance increased to a value exceeding the resistance of the winding 12^a, engagement of the contact members 13 and 20 may be effected by 110 opening and immediately reclosing the switch 10.

115 The actuation of the relays 24 and 25 may thus be effected as desired, and the operation of the devices in the corresponding circuits may be controlled by the corresponding switches 26 and 27.

120 It will be observed that, by utilizing the thermal-resistance characteristic of an electrical conductor, the resistance of which varies in accordance with the temperature, devices may be simply controlled from a distance by means of a single circuit and a single control switch, and a large saving 125 effected thereby in the cost of conductors.

130 My invention is not limited to the specific construction of the devices that are illus-

trated, or to the specific arrangement thereof, since they may be variously modified and arranged within the spirit and scope of my invention, as set forth in the appended 5 claims.

I claim as my invention:—

1. The combination with a source of energy and a plurality of translating devices having temperature-resistance coefficients 10 and remotely disposed with respect to said source of energy, of a single circuit therebetween, and means responsive to the variation of the resistance of the translating devices by reason of the temperature-resistance 15 coefficients thereof for selectively controlling the connection of the circuit to the several translating devices.
2. The combination with a source of energy and a plurality of translating devices 20 remotely disposed with respect thereto, of a single circuit therebetween and means in said circuit for selectively controlling the connection of the circuit to one of the devices, comprising means dependent upon the thermal-resistance characteristics of said devices. 25
3. The combination with a lighting system comprising two groups of light-producing devices and a source of energy remotely disposed with respect thereto, of a balance 30 relay connected between the two groups and the source of energy, and means for controlling the operation of the relay dependent upon the thermal-resistance characteristics of said devices for selectively connecting the 35 source of energy to one of the groups.
4. The combination with a lighting system comprising two groups of light-produc-

ing devices and a source of energy remotely disposed with respect thereto, of a balance 40 relay connected between the two groups and the source of energy, and a circuit-controlling device between the relay and the source of energy for selectively controlling the operation of the relay in accordance with the thermal condition of the light-producing devices. 45

5. The combination with a lighting system comprising two groups of light-producing devices having temperature-resistance coefficients and a source of energy remotely 50 disposed with respect thereto, of an electro-responsive device embodying two windings respectively connected in circuit with the two groups of light-producing devices and between both groups and the source of energy, and a switching device in the circuit between the source of energy and the relay windings for selectively controlling the relay according to the temperature-resistance 55 coefficients of the light-producing devices. 60

6. The combination with two devices embodying temperature-resistance coefficients and a source of energy remotely disposed with respect thereto for energizing said devices, of a single conductor therebetween 65 and means controlled through said conductor and dependent upon said temperature-resistance coefficients for effecting the connection of the source of energy through said conductor to either device. 70

In testimony whereof, I have hereunto subscribed my name this 6th day of July, 1921.

EDGAR W. BREISCH.
